(57) CLAIM

The ornamental design for a golf club face, as shown and described.

DESCRIPTION

FIG. 1 is a front perspective view of a golf club face;
FIG. 2 is a front elevational view of the golf club face of FIG. 1;

FIG. 3 is a top view of the golf club face of FIG. 1;
FIG. 4 is a heel end view of the golf club face of FIG. 1; and,
FIG. 5 is a toe end view of the golf club face of FIG. 1.

The broken lines shown in the above figure(s) are for illustrative purposes only and form no part of the claimed design.
